UNITED STATES PATENT OFFICE

94,699

DESIGN FOR AN INHALANT DEVICE

Robert E. Linn, Detroit, Mich., assignor to
Thomas J. McCormick, Detroit, Mich.

Application November 22, 1933, Serial No. 49,824

Term of patent 14 years

To all whom it may concern:

Be it known that I, Robert E. Linn, a citizen of the United States, residing at Detroit, in the county of Wayne and State of Michigan, have invented a new, original, and ornamental Design for an Inhalant Device, reference being had to the accompanying drawing, forming part thereof.

Figure 1 is a perspective view of the inhalant device, showing my new design.

Figure 2 is a view of the device with the cover removed.

What I claim is:

The ornamental design for an inhalant device, substantially as shown and described.

ROBERT E. LINN.
